METAL FABRIC MAKING MACHINE

Herbert E. White, Lakewood, Ohio, assignor to
Wire Fabric Corporation, a corporation of California

Application September 28, 1935, Serial No. 42,698

26 Claims. (Cl. 140—112)

The present invention relates to machines for manufacturing open mesh wire fabric and is particularly devised for producing that type in which continuous strands are used that are laid in crossed relation and united at their points of crossing, preferably by welding.

The object is to provide a simple and effective machine of a novel character that will accurately function and produce a fabric in which the strands are evenly spaced and are effectively secured together.

In this latter connection, the mechanism is preferably so constructed that the uniting means, as electric welding devices operate while the fabric is at a standstill, and a better welding action is thereby obtainable.

In the accompanying drawings:

Figure 1 is a top plan view of an embodiment of the invention which is at present considered the preferable one.

Figure 2 is a plan view of the strand laying mechanism at the completion of its movement in one direction.

Figure 3 is an end elevation of the machine at the fabric forming end.

Figure 4 is a detail vertical sectional view of the line 4—4, Figure 1.

Figure 5 is a side elevation of the carriage supporting means looking in the direction of the arrow A of Figure 2.

Figure 6 is a vertical sectional view on the line 6—6 of Figure 1.

Figure 7 is a detail sectional view on an enlarged scale of the transferring pin hook shown in Figure 6 and illustrating its action on the adjacent strand.

Figure 8 is a cross sectional view on the line 8—8 of Figure 7.

Figure 9 is a side elevation, partly broken away, of the welding mechanism.

Figure 10 is a vertical sectional view on the line 10—10 of Figure 9.

Figure 11 is a sectional view on the line 11—11 of Figure 9.

Figure 12 is a detail view showing the elevating means for the electrodes.

Figure 13 is a detail view showing one of the cam tracks for the holding pins of the conveyor.

Figure 14 is a sectional view on the line 14—14 of Figure 13.

Figure 15 is a plan lay-out of the controlling mechanism for the various motors.

Referring to Figure 1, a fabric conveyor is provided made up of two endless conveyor belts or chains 16 that are horizontally disposed and

have inner stretches 17 and outer stretches 18. These chains operate on horizontally disposed sprocket wheels 19 and 20. The sprocket wheels 20 are carried on the upper portions of vertical shafts 21 whose lower ends are provided with worm gears 22. These worm gears are engaged by driving worms 23 carried by a horizontal shaft 24 that is an extension of the rotary piston shaft of a fluid operated rotary motor 25. The operation of the motor 25, therefore, will cause the movement of the two conveyor chains 16, and this is effected so that the inner or adjacent stretches 17 thereof move in the direction of the arrow B of Figure 1. It will be noted that one of the conveyors 16 is shorter than the other, and consequently the drive shaft 24 is located diagonally to the said conveyors.

Arranged alongside the driving mechanism 24—25 and diagonally disposed with respect to the conveyors 16 and located above the same is a pair of spaced trackways 26 having secured to their inner sides racks 27. On the trackways reciprocates a strand laying carriage 28 which includes a main frame piece 29 that extends parallel to the conveyors. A rotary shaft 30 journaled on the frame has gears 31 which mesh with the racks 27. By rotating the shaft 30 in opposite directions the carriage will be reciprocated diagonally across the space between the inner stretches 17 of the conveyors' chains 16. To accomplish this the shaft 30 has at one end a beveled gear 32 in mesh with a beveled gear 33 splined to a diagonal drive shaft 34 that extends along one of the guide tracks 26. The gear wheel 33, it will be understood, moves with the carriage 28 by being journaled in a bracket 35 fixed to the carriage and have a key engaged in a longitudinal key-way 36 formed in the shaft 34. This shaft 34 is adapted to be rotated in opposite directions by a reversible rotary fluid operated motor 37. If then the motor 37 is rotated alternately in opposite directions, the carriage 28 will obviously be reciprocated diagonally back and forth across the conveyor stretches 17.

The means for engaging the continuous strands of wire and laying said strands in proper relation will now be described.

The two conveyor chains 16 are provided with a plurality of up-standing pins 38 that are mounted to slide vertically in the connections between the chain links (see Figures 13 and 14). Their lower ends are provided with heads 39 having annular grooves 40 in which are engaged fixed cam tracks 41 located beneath the inner stretches 17 of the conveyors and thus governing the posi-

tions and vertical movements of the pins as they travel with the conveyor chains. The fabric is formed by the location of the continuous strands in crossed relation and engaged around said pins as shown at the left in Fig. 1. These strands, where they are delivered to the machine and designated 42, are supplied from any suitable sources and preferably enter the machine diagonally at the end of the carriage way parallel to the path of travel of said carriage and operate over suitable idler rollers 43. Thence they pass about or alongside (depending on the position of the carriage) pins 44 on a fixed portion of the frame and located outside the adjacent inner stretch 17 of the conveyor belt (see Figure 2). By referring to Figure 1, it will be noted that when the carriage is at the further end of its path, the strands 42 bend about the pins 44 and extend to a successive series of the up-standing pins 38 of the conveyor, thence as shown at 42a they extend diagonally across the space between the conveyor chains and then back again so that they are crossed into a diagonal mesh formation.

In order to get these strands across the said space and to the pins of the opposite conveyor belt the part 29 of the carriage, as shown in detail in Figures 6 and 7, has a series of vertically disposed depending transfer pins 45. The pins are vertically movable in the part 29 and are also rotatable therein. They are provided at their lower ends with hook extensions 46 that are adapted to lie alongside the pins 44 and rotate about the same. These pins 45 are provided with circular rack teeth 47 engaged by segment gears 48 that are fixed to a horizontal shaft 49 journaled on the carriage part 29. The upper ends of the pins 45 slidably pass through worm gears 50 to which they are splined as shown at 51. The worm gears are in mesh with worms 52 on a horizontal shaft 53 carried by the carriage part 29. The shaft 49 has a beveled gear 54 in mesh with another beveled gear 55 that is slidably splined on a rock shaft 56 journaled along the outer trackway 26. This rock shaft has a crank arm 57 connected by a link 58 to the piston rod 59 of a reciprocating motor 60 (see Figure 5). The other shaft 53 of the carriage has a beveled gear 61 meshed with another beveled gear 62 slidably splined to a drive shaft 63 that extends longitudinally alongside the shaft 56. The shaft 63 also has a crank arm 64 linked as shown at 65 to the piston rod 66 of a reciprocating motor 67 located beside the motor 60. By reciprocating the motors 60 the segment gears 48 will be turned in opposite directions thus raising and lowering the pins 45 and by operating the motor 67 the worms 52 will be turned in opposite directions thereby correspondingly rotating the pins 45 and the hooks 46.

The operation of this part of the mechanism, it is believed, can now be explained. Assuming the parts as shown in Figure 1 with the strands 42 bent around the pins 44, it will be evident that if segment gears 48 turn downwardly, the pins 45 will be lowered and the hooks 46 will lie alongside the strands 42 as shown in Figure 7. If now the pins 45 are partially rotated by operating the shaft 53, these hooks will pass around the pins, as shown in Figure 8. The fingers 45 are now again raised carrying the strands above the tops of the pins 44. When so arranged, the motor 37 is operated thereby turning the shaft 30 and causing its gears 31 to ride along the racks 27 in a direction to carry the carriage to the left hand side of the machine or to the posi-

tion shown in Figure 2. This, it will be noted, causes the portions of the strands that lie longitudinally along the outer of the two stretches 17 to swing across the space between the two stretches. The pins 45 now come over the pins 5 of the left-hand stretch 17 and here they are depressed so that the bights of the strands now partially surrounding them are brought down around the up-standing pins of the conveyor. The rotation of the pins 45 now takes place so as to release the hooks 46 after which pins are elevated so as to clear all obstructions and the carriage returns to the position shown in Figure 1. It is to be noted that in this operation the strands are carried across in one direction only and that the said strands which extend from the nearer up-standing pins toward the feed lie in their proper parallel angular relation. The return movement of the carriage, therefore, is an idle one.

Referring now to the strand uniting mechanism which is designated generally by the reference numeral 68, this is a welding apparatus and is stationarily mounted at one side of the strand laying mechanism above described. It preferably consists of an upper set of depending electrodes 69 and a lower up-standing coating set 70 arranged, of course, to engage the opposite sides of the fabric at the crossing points of the strands. The upper electrodes 69 are preferably fixed in a suitable top plate 71 carried on standards 72 and located above the inner stretches 17 of the conveyor chains (see Figure 10). The lower electrodes 70 are preferably yieldingly mounted as shown at 73 and are carried by a vertically movable support 74 having collars 75 that are slidably mounted on said standards 72. The support and therefore the lower electrodes 70 are moved upwardly by vertically moving pistons forming parts of motor 76. It will be understood that these sets of electrodes are suitably connected as by bars 77 with a secondary circuit 78 of a transformer 79 and this transformer is in an electric circuit 80 which includes a controlling switch 81 that is geared as shown at 82 in Figure 1 with the carriage drive shaft 36.

The arrangement is such that the conveyor chains 16 are intermittently operated and when they are at rest the carriage 28 is operated, the lower electrodes are elevated and current is supplied to the transformer and consequently to the electrodes.

In order to accomplish this, controlling mechanism is employed which is shown somewhat diagrammatically in Figure 15. A main supply line 55 of fluid under pressure is shown at 83 and has connections with the various motors above described. An exhaust pipe 84 correspondingly leads from these motors.

Considering the control means for each motor 60 individually, and referring first to the motor 25 which effects the intermittent operation of the conveyor 16-16, a valve 85 is provided that is of the ordinary spool type and reciprocates in a valve casing 86. The supply conduit 83 is connected to this valve casing as shown at 87 and from the valve casing a delivery pipe 88 leads to the motor 25. Obviously, when the valve is moved to one end of the casing, the delivery pipe 88 will be in communication with the supply pipe 83 through 87 and the motor 25 will be operated. The valve is operated in one direction by a cam 89, fixed to a shaft 90 and driven by a variable speed motor 91. As it is essential that the amount of movement of the conveyor be accu-

5 rately determined, the movement of the valve 85 in an opposite direction to cut off the supply of motive fluid and thus stop the motor is governed by a timing valve 82 operated by a cam 83 on the shaft 24. A branch line 85 leads from the supply pipe 83 to this valve and a delivery pipe 86 leads from the valve to the end of the valve chamber 86. Thus the valve 82 at the proper time will admit fluid to the casing 86 and move 10 the valve in a direction opposite to that in which it is moved by the cam 88, thereby cutting off the supply of fluid to the motor 25 as will be clear by the position of the valve in Figure 15.

15 The motor 87 is controlled by a valve 97 that is operated by a cam 98 on the shaft 90. This valve is located in a casing 99 which is supplied with fluid under pressure from the line 83 by the branch 100. A supply pipe 101 leads from the valve casing to the motor and an exhaust pipe 102 leads from the motor to the main exhaust line 84. In this case the valve 97 is returned after 20 its movement by the cam 98 by a spring 103 placed behind it.

25 The motor 60 is controlled by a valve 104 operated in one direction by a cam 105 on the shaft 90 and operated in the opposite direction by a spring 106. This valve controls the supply pipe 107—101a leading to the motor 60.

30 The motor which causes the reciprocatory traverse of the carriage 28—29 is reversible and in the structure shown its operation in opposite directions is controlled by two valves designated respectively 108 and 109. These are actuated by the cams 110 and 111 on the shaft 90. As illustrated the supply line 83 is connected to a branched pipe 112 that supplies a motive fluid to the valve casing of said valves 108 and 109. Leading from the two valve casings are pipes 113 and 114 that connect to a common pipe 115 entering one side of the motor 37, this system 35 113—114—115 acting either for supplying motive fluid to the motor 37 or exhausting the motor fluid therefrom, depending in which direction the motor is operated. Another set of pipes 116 and 117 also lead from the valve casings 108 and 109 to a common pipe 118 that is connected to the opposite side of the motor from the pipe 115. This system 116—117—118 also alternately acts 40 as motor fluid supply and exhaust means. The 45 casings of the valves 108 and 109 are also in communication with an exhaust pipe 119 that leads to the exhaust main 84.

50 It will be clear that if the valve 109 is moved from the position shown in Figure 15 by the cam 111, it will afford communication between the supply pipe 112 and the delivery pipe 113 and thus motive fluid will be directed into one side of the motor 37. The exhaust from the motor 37 will take place through the pipes 118, 117, 119 and 84 because the pipes 117 and 119 are not in communication. When the valve 109 returns to the position shown and the other valve 100 is moved by its cam 110, then a reverse action will take place. That is to say, motive fluid supplied 55 through the pipe 112 will pass through pipes 114 and 115 to the opposite side of the motor 37 while the exhaust will now take place through the pipe 118, 116, 119 and 84.

60 The motors 76 which elevate the lower set of electrodes 70 are, of course, simultaneously actuated and a supply pipe 120 has a manifold connection 121 with said motors. This supply pipe leads from the valve casing 122 of a valve 123 adapted to be actuated by a cam 124 on the shaft 75 70 76. An exhaust manifold 125 leading from the

motors 76 is connected to a pipe 126 that is also connected to the valve casing 122. A branch supply pipe 127 leads from the main 83 and a return exhaust pipe 128 leads from the casing 122 to the exhaust main 84. The arrangement of 5 this valve is such that when actuated by the cam 124 motive fluid passes from the branch 127 into the pipe 126 and manifold 121 thus delivering motive fluid below the pistons of the motors 76 and elevating the lower electrodes. The fluid 10 above the pistons of said motors exhausts through the pipe 126 and pipe 128 into the main 84. When the valve 123 moves in the opposite direction then the pipe 128 is brought into communication with the supply branch 127 delivering 15 the motive fluid above the pistons of the motors 76 and again depressing the electrodes. The space below the pistons of the motors 76 is now open to exhaust through the pipe 120, pipe 128 and exhaust main 84. 20

25 It will be understood that the various cams on the shaft 90 are so formed and related that they will effect the carrying out of the movements of the different parts in definite pre-determined relation so that the mechanisms will operate accurately. Thus when the conveyor is at a standstill there will be a complete assembly of the crossed strands between the upper and lower sets of electrodes. These electrodes at this time will 30 be brought into contacting relation with the strands at their crossing points. The timer 81 will now operate to energize all electrodes and secure the electric welding together of the strands. This, it will be noted, is accomplished while the 35 fabric is at rest so that an effective weld is obtained. At this time also the carriage reciprocates, carrying another set of strands across the space between the conveyors, engages them with the up-standing pins and then said carriage returns to its initial position shown in Figure 1. The welding and strand laying operations being 40 now complete, the conveyor is thrown into operation thus moving another section of crossed strands into position to be welded, carrying the last set of diagonal strands onward out of the 45 way of the carriage and leaving the entering strands in position to be again brought across by the carriage on the next operation.

50 From the foregoing, it is thought that the construction, operation and many advantages of the herein described invention will be apparent to those skilled in the art without further description and it will be understood that various changes in the size, shape, proportion and minor 55 details of construction may be resorted to without departing from the spirit or sacrificing any of the advantages of the invention.

56 What I claim is:

1. In apparatus for the manufacture of wire 60 fabric, the combination with means for intermittently moving the fabric strands in a predetermined path, of means for carrying bights of the said strands diagonally across said path, while the fabric strand moving means is at rest. 65

2. In apparatus for the manufacture of wire 70 fabric, the combination with means for intermittently moving the formed fabric in a predetermined direction, of means for carrying a bight of each fabric forming strand diagonally of the 75 said line of direction, while the fabric strand moving means is at rest.

3. In apparatus for the manufacture of wire 75 fabric, the combination with fabric forming means, of means for periodically moving the same, 75

- and means for supplying bights of the fabric forming strands to the forming means, during its periods of rest.
4. In apparatus for the manufacture of wire fabric, the combination with a fabric carrier having a periodic movement and being substantially at rest between its periods of movement, of a mechanism for supplying and forming continuous strands, and means for moving the strand supplying mechanism and the carrying means alternately.
5. In apparatus for the manufacture of wire fabric, the combination with a fabric conveyor having an intermittent movement, of a laying mechanism for applying continuous strands in the form of bights and intermittently movable across the fabric conveyor, and mechanism for moving the conveyor and laying mechanism alternately.
- 10 6. In apparatus for the manufacture of wire fabric, the combination with a conveyor having means for holding diagonally crossed strands thereupon, of a strand laying carriage operating diagonally across the conveyor and delivering the strands thereto in continuous lengths.
- 15 7. In apparatus for the manufacture of wire fabric, the combination with a conveyor having spaced means for holding strands in crossed relation, of mechanism movable across the conveyor for swinging strands that are engaged with one means across the conveyor to the other means.
- 20 8. In apparatus for the manufacture of wire fabric, the combination with a conveyor having spaced means for holding strands in crossed relation, of mechanism movable diagonally across the conveyor for swinging strands that are engaged with one means across the conveyor to the other means.
- 25 9. In apparatus for the manufacture of wire fabric, the combination with a conveyor having spaced means for holding strands in crossed relation, of mechanism movable across the conveyor for swinging the strands that are engaged with one means, and using said means as pivot axes, across the conveyor and in the direction of movement of the conveyor.
- 30 10. In apparatus for the manufacture of wire fabric, the combination with a conveyor comprising endless belts having spaced correspondingly travelling stretches and devices on said stretches for holding the selvage bights of the fabric strands, of means for delivering strands across the space between the belts, and to positions to be engaged by said holding devices.
- 35 11. In apparatus for the manufacture of wire fabric, the combination with a conveyor comprising endless belts having respectively inner and outer stretches, the inner stretches of the belts being spaced apart and travelling in the same direction, and devices on said belts for holding the selvage bights of the fabric strands, of means for delivering strands across the space between the belts and to positions to be engaged by said holding devices.
- 40 12. In apparatus for the manufacture of wire fabric, the combination with a fabric forming conveyor, of a carriage movable across the same to lay bights of the strands thereon, the said carriage laying the strands during its travel in one direction only.
- 45 13. In apparatus for the manufacture of wire fabric, the combination with a fabric forming conveyor, of means for forming diagonally crossed continuous strands including a carriage movable across the conveyor and having means
- for repeatedly forming and carrying bights of the strands in one direction only across the conveyor.
- 50 14. In apparatus for the manufacture of wire fabric, the combination with a fabric forming conveyor having spaced sets of holding devices for engagement with the bights of crossed continuous strands, of means for delivering strands to positions to engage one set of holding devices, a carriage movable across the conveyor, and means on the carriage for engaging the strands engaged with said set and carrying them across the conveyor to engage the holding devices of the other set.
- 55 15. In apparatus for the manufacture of wire fabric, the combination with a fabric forming conveyor having spaced sets of holding devices for engagement with the bights of crossed continuous strands, of means for delivering strands to positions to engage one set of holding devices, a carriage movable across the conveyor, fingers on the carriage for engaging the strands engaged with said set and carrying them across the conveyor to engage the holding devices of the other set, and means for relatively moving the fingers and holding devices to transfer the strands from the fingers to the devices.
- 60 16. In apparatus for the manufacture of wire fabric, the combination with a fabric forming conveyor having spaced sets of holding devices for engagement with the bights of crossed continuous strands, of means for holding strands to positions to engage one set of holding devices, a carriage movable across the conveyor, reciprocating fingers on the carriage for engaging the strands to carry them across the conveyor to engage the holding devices of the other set, and means for reciprocating the fingers to cause them to engage the strands at one side of the conveyor and to release the same at the other side.
- 65 17. In apparatus for the manufacture of wire fabric, the combination with a fabric forming conveyor having spaced sets of holding devices for engagement with the bights of crossed continuous strands, of means for delivering strands to positions to engage one set of holding devices, a carriage movable across the conveyor, reciprocating and rotary finger hooks on the carriage for engaging the strands to carry them across the conveyor to engage the holding devices of the other set, and means for reciprocating and rotating the fingers to cause them to engage the strands at one side of the conveyor and to release the same at the other side.
- 70 18. In apparatus for the manufacture of wire fabric, the combination with a fabric forming conveyor having spaced sets of upstanding pins for engagement with the opposite selvage bights of the fabric, of a reciprocating carriage movable diagonally across the conveyor, means for supplying continuous strands to one set of conveyor pins, leaving free portions extending generally longitudinally along the set, depending pins on the carriage that are reciprocably mounted thereon, means for depressing the pins to engage the free portions of the strands, means for moving the carriage across the conveyor when the pins are depressed and causing said pins to attain a position to deliver the strands to the other set of conveyor pins, and means for withdrawing the carriage pins from the strands when so positioned.
- 75 19. In apparatus for the manufacture of wire fabric, the combination with a fabric forming conveyor having spaced sets of upstanding pins

- for engagement with the opposite selvage bights of the fabric, of a reciprocating carriage movable diagonally across the conveyor, means for supplying continuous strands to one set of conveyor pins, leaving free portions extending generally longitudinally along the set, depending hooked pins on the carriage that are reciprocably and rotatably mounted thereon, means for depressing the pins and rotating them to engage the 5 free portions of the strands, means for moving the carriage across the conveyor when the pins are depressed and causing said pins to attain a position to deliver the strands to the other set of conveyor pins, and means for rotating and 10 withdrawing the carriage pins from the strands when so positioned. 15
20. In apparatus for the manufacture of wire fabric, the combination with a conveyor comprising spaced endless belts having upstanding pins for engaging the selvage bights of crossed continuous fabric strands, of means for raising and lowering said pins, means for supplying strands to one set of pins, a carriage movable diagonally across the conveyor from one belt to 25 the other, means for moving and stopping the conveyor and carriage alternately, depending carrier hooks slidably and rotatably mounted on the carriage and moving from one set of upstanding conveyor pins to the other set, and 30 means for depressing the hooks and rotating them to engage the strands at one set of conveyor pins and while the carriage is at rest, and for rotating the hooks and rotating them when the same are at the other set of conveyor pins and while 35 the carriage is again at rest after a movement. 21. In apparatus for the manufacture of wire fabric, the combination with a conveyor comprising spaced endless belts having upstanding pins for engaging the selvage bights of crossed continuous fabric strands, of means for raising and lowering said pins, means for supplying strands to one set of pins, a carriage movable diagonally across the conveyor from one belt to the other, motors for respectively moving the conveyor and 40 carriage, depending carrier hooks slidably and rotatably mounted on the carriage and moving from one set of upstanding conveyor pins to the other set, a motor means for depressing the hooks and rotating them to engage the strands at 45 one set of conveyor pins and while the carriage is at rest, and for rotating the hooks and rotating them when the same are at the other set of conveyor pins and while the carriage is again at rest after a movement, and controlling means for operating the motors in predetermined timed relation. 50
22. In apparatus for the manufacture of wire fabric, the combination with a conveyor comprising spaced endless belts having upstanding pins for engaging the selvage bights of crossed continuous fabric strands, of means for raising and lowering said pins, means for supplying strands to one set of pins, a carriage movable diagonally across the conveyor from one belt to the other, fluid actuated motors for respectively moving the conveyor and carriage, depending carrier hooks slidably and rotatably mounted on the carriage and moving from one set of up- 55
- standing conveyor pins to the other set, a motor means for depressing the hooks and rotating them to engage the strands at one set of conveyor pins and while the carriage is at rest and for rotating the hooks and rotating them when the same are at the other set of conveyor pins and while the carriage is again at rest after a movement, valves controlling the supply of motive fluid to the motors, and means for actuating the valves in predetermined timed relation. 5
23. In apparatus for manufacturing wire fabric, the combination with a conveyor, of means at one point for supplying strands to the conveyor to form the fabric, means at another point for welding the strands together, means for intermittently moving the conveyor to carry the assembled strands from the supplying means to the conveyor, and means operating during the intermission of movement of the conveyor to cause the welding means to act on the portion of assembled strands delivered thereto by a preceding movement of the conveyor. 10
24. In apparatus for manufacturing wire fabric, the combination with a conveyor, of means at one point for supplying strands to the conveyor to form the fabric, means at another point for welding the strands together, means for intermittently moving the conveyor to carry the assembled strands from the supplying means to the conveyor, and means operating during the intermission of movement of the conveyor to cause the fabric supply means to deliver the strands to the conveyor and to cause the welding means to act on the portion of assembled strands delivered thereto by a preceding movement of the conveyor. 15
25. In apparatus for manufacturing wire fabric, the combination with a conveyor on which the fabric is laid out, of means at one point operating to supply the strands to and assemble them on the conveyor, means at another point for welding together the assembled strands, means for intermittently operating the conveyor to carry the assembled strands from the assembling means to the welding means, mechanism for operating the assembling means when the conveyor is at rest to form a section of the fabric, and mechanism for operating the welding means when the conveyor is at rest to weld a section of the formed fabric delivered thereto by the conveyor. 20
26. In apparatus for manufacturing wire fabric, the combination with a conveyor for carrying fabric formed thereon, of mechanism at one point of the conveyor for supplying continuous strands and for assembling the same into fabric form on the conveyor, a welding apparatus at another point of the conveyor for welding together the strands of the fabric formed by said mechanism, a motor for moving the conveyor, a motor mechanism for operating the forming mechanism, a motor for actuating the welding apparatus, and means for controlling the operations of the various motors to cause the conveyor to operate intermittently and to cause the forming mechanism and welding apparatus to operate when the conveyor is idle. 25

HERBERT E. WHITE.
